UNITED STATES PATENT OFFICE

97,433

DESIGN FOR AN IRONING MACHINE

Alfred W. Draeseke, Jamestown, N. Y., assignor
to Jamestown Metal Equipment Company, Inc.,
Jamestown, N. Y., a corporation of New York

Application September 11, 1935, Serial No. 58,517

Term of patent 14 years

To all whom it may concern:

Be it known that I, Alfred W. Draeseke, a citizen of the United States, residing at Jamestown, in the county of Chautauqua and State of New York, have invented a new, original, and ornamental Design for an Ironing Machine, of which the following is a specification, reference being had to the accompanying drawing, forming part thereof, and in which

Figure 1 is a front view in perspective of an ironing machine showing my new design;

Figure 2 is a plan view; and

Figure 3 is a perspective end view.

I claim:

The ornamental design for an ironing machine as shown.

ALFRED W. DRAESEKE.
